UNITED STATES PATENT OFFICE.

THOMAS K. OBER, OF PHILADELPHIA, PENNSYLVANIA.

BRAIDING-MACHINE.

SPECIFICATION forming part of Letters Patent No. 641,880, dated January 23, 1900.

Application filed March 3, 1899, Serial No. 707,578. (No model.)

To all whom it may concern:

Be it known that I, THOMAS K. OBER, residing in the city of Philadelphia, State of Pennsylvania, have invented certain new and useful Improvements in Braiding-Machines, of which the following is a specification.

This invention is more particularly an improved machine for plaiting threads drawn from bobbins revolving in opposite directions in which special mechanisms are employed for operating the bobbin-carriers for one set of threads and for guiding the other set of threads alternately above and below the said bobbin-carriers in the serpentine courses required for plaiting or braiding.

The primary objects of the improvements are to obtain increased speed, to reduce wear, to avoid irregular action, to simplify the construction of the bobbin-carrying mechanism, and to improve the thread-guiding mechanism.

In the accompanying drawings, Figure 1 is a side elevation of a machine embodying my invention. Fig. 2 is a top plan view of the same. Fig. 3 is a central sectional elevation illustrating the improvement. Fig. 4 is a sectional view, in front elevation, of the raceway, carrier, and carrier-operating mechanism. Fig. 5 is a sectional view at right angles to that shown in Fig. 4, illustrating the raceway, carrier, and carrier-operating mechanism. Fig. 6 is a sectional view, in front elevation, of a modified form of carrier-operating mechanism.

As illustrated in the drawings, the base 1, the standards 2, and the cross-bar 3 form a suitable frame for the mechanism. This framework supports a cylindrical casing 4, which is separated into two sections on the line of the compound curve 5. Its upper section is supported by the standards 2 and its lower section by the spider 6 and the fixed column 7, the spider being secured to the column and the column to the base.

A revolute shaft 8, journaled in bearings 9 and 10, has a bevel gear-wheel 11 fixed on its inner end. The gear-wheel 11 engages with a bevel gear-wheel 12, fixed on the lower end of a revolute hollow shaft 13, which is

journaled within the hollow column 7, and

with a bevel gear-wheel 14, fixed on the lower end of a revolute hollow shaft 15, which is journaled upon the column 7.

A revolute spider 16 is fixed upon the upper end of the shaft 13, the spider supporting hangers 17 for the shafts 18, which are journaled therein. The inner end of each shaft 18 has fixed thereon a gear-wheel 19, which is engaged by a circular gear-track 20, fixed upon the stationary spider 6. The outer end of each shaft 18 has fixed thereon a crank 21, whose pin 22 reciprocates within a yoke 23 on the lower end of a reciprocating pin 24. It will be understood that mechanical variations in the form of the eccentric connection and of the operating mechanism for the same may be made.

Each pin 24 reciprocates through a guide-way 25 in the spider 16, and thus alternately engages and disengages with a corresponding aperture 26 in a carrier 27. The pins 24 and their respective operating mechanisms are arranged in pairs, so that while one is rising to engage the corresponding carrier the other is falling to disengage with the carrier, the arrangement being such that each carrier is always engaged by one of its two reciprocating pins.

As illustrated in Fig. 6, the respective pairs of pins 24 may be reciprocated by rocking levers 24', pivoted to said pins and to a hanger 25'. This lever may be rocked by the engagement of its yoke 23' with the pin 22' of the crank 21', the crank being operated by the gear heretofore described.

The carriers 27 are mounted upon a circular sectional raceway 28, supported by the casting 4 intermediate of the highest and lowest points of the serpentine aperture 5, which divides the raceway into sections located alternately above the lowest and below the highest points of the compound curve for the passage of the threads from the lower bobbins 44. Each of the series of bobbins 29 is journaled between the arms 30 of its carrier and supplies threads through the tension device 31 to the plaiting-point 32. This special form of raceway and bobbin-carrier are of well-known construction.

A revolute spider 33 is fixed upon the up-

100

per end of the journaled shaft 15, the spider supporting the hangers 34 for the shafts 35, which are journaled therein. The inner end of each shaft 35 has fixed thereon a gear-wheel 36, which engages with a circular gear-track 37, fixed to the stationary spider 6. The outer end of each shaft 35 has fixed thereon a crank 38, whose pin 39 reciprocates within a yoke 40 of a thread-guide 41. Each thread-guide 41 reciprocates in a guideway 42, supported by an extension of an arm 43, which is carried by the revolute gear-wheel 14. Each of the series of bobbins 44 is journaled between the spider 33 and the corresponding arm 43 and supplies thread through its thread-guide 41, through the serpentine aperture 5, to the plaiting-point 32. The character of the eccentric and its operating mechanism for the thread-guides may be varied in mechanical details.

In the operation of the machine the revolution of the shaft 8 and the gear-wheel 11, fixed thereon, revolves the gear-wheels 12 and 14 in opposite directions, thus revolving in opposite directions the spiders 16 and 33, connected with the respective gear-wheels 12 and 14 by the revolute shafts 13 and 15. The revolution of the spider 16 carries the gear-wheels 19 around the gear-track 20, thus revolving the shafts 18 and cranks 21 and reciprocating in opposite directions the pins 24 of each pair, so that each carrier 27 is always engaged by one of its pins and moved along the raceway 28 in unison with the revolution of the spider 16. The revolution of the spider 33 carries the gear-wheels 36 around the gear-track 37, thus revolving the shafts 35 and cranks 38 and reciprocating the thread-guides 41, the reciprocations of the guides being timed so that their upper ends rise and fall in a path parallel to the serpentine aperture 5 of compound curve. The opposite reciprocations of the pins 24 are timed so that they are drawn down alternately to pass the thread from the lower bobbins 44 when these threads are being moved beneath the carriers by their guides. It will be observed that the respective threads from the lower series of revolving bobbins are fed from their guides at the elevations required for passing alternately above and below the oppositely-revolving carriers and bobbins, causing the two sets of threads passing to the plaiting-point to be interlaced, drawing threads from the bobbins at the uniform rates required without dragging them or requiring take-up devices, as in machines heretofore employed.

Having thus described my invention, I claim—

60 1. In a braiding-machine, a stationary gear-track, a gear-wheel revolved by said gear-track, a reciprocating pin, a carrier arranged to be engaged by said pin and eccentric mechanism operated by said gear-wheel for reciprocating said pin, in combination with a rev-

oluble spider which carries said mechanism, through which said pin reciprocates, substantially as specified.

2. In a braiding-machine, a fixed circular gear-track, a journaled gear-wheel revolute 70 upon said track, a reciprocating pin revolute with said gear-wheel, mechanism operated by said gear-wheel for reciprocating said pin, and a movable carrier alternately engaged and disengaged by said pin, substantially as specified. 75

3. In a braiding-machine, a fixed circular gear-track, a pair of journaled gear-wheels revolute upon said track, a pair of reciprocating pins revolute with said gear-wheels, eccentric mechanisms connecting said gear-wheels with said pins whereby said pins are reciprocated oppositely, and a movable carrier alternately engaged and disengaged by each of said pins, substantially as specified. 80

4. In a braiding-machine, a journaled shaft, 85 a spider fixed thereon, a journaled gear-wheel supported by said spider, a fixed circular gear-track upon which said gear-wheel revolves, a movable carrier, a pair of oppositely-reciprocating pins for operating said carrier, mechanism operated by said gear-wheel for reciprocating one of said pins, and means for effecting the opposite reciprocation of the other of said pins, substantially as specified. 90

5. In a braiding-machine, a stationary gear-track, a gear-wheel revolved by said gear-track, a reciprocating thread-guide, and mechanism operated by said gear-wheel for reciprocating said thread-guide, in combination with a revolute spider which carries the 100 aforesaid mechanism, and a bobbin carried by said spindle, substantially as specified. 95

6. In a braiding-machine, a fixed circular gear-track, a journaled gear-wheel revolute upon said gear-track, a reciprocating thread-guide, ways for controlling the movements of said thread-guide, and mechanism operated by said gear-wheel for reciprocating said thread-guide, substantially as specified. 105

7. In a braiding-machine, a sectional race-way, a bobbin-carrier movable thereon, a revolute spider, a pair of alternately-reciprocating pins passing through said spider and engaging with said carrier, a yoke in each of said pins, a crank-and-pin connection for each 110 of said yokes, a shaft for revolving each of said cranks, and means for revolving said shafts, substantially as specified.

8. In a braiding-machine, a fixed circular gear-track, a revolute frame, a series of gear-wheels journaled in said frame and revolute upon said gear-track, a series of pins arranged in pairs passing through said frame, mechanism connecting said gear-wheels with said pins for reciprocating said pins, a series of movable bobbin-carriers each operated by a pair of said pins, a sectional raceway for said bobbin-carriers, in combination with a second fixed circular gear-track, a second revolute frame, a second series of gear-wheels jour- 125 130

naled in said second frame and revoluble upon said second gear-track, a series of reciprocating thread-guides, mechanism operated by each of said second series of gear-wheels for reciprocating each of said thread-guides, and mechanism for revolving said frames in opposite directions, substantially as specified.

In testimony whereof I have hereunto affixed my signature in the presence of the subscribing witnesses.
